UNITED STATES PATENT OFFICE

FRANK WAVPOTICH AND LOUIS F. WANEK, OF ASTORIA, NEW YORK

DESIGN FOR A DOUBLE-EDGE RAZOR BLADE SHARPENER

Application filed November 14, 1931. Serial No. 41,735. Term of patent 7 years.

To all whom it may concern:

Be it known that we, FRANK WAVPOTICH and LOUIS F. WANEK, citizens, respectively, of Yugoslavia and United States, and residents of Astoria, county of Queens, and State of New York, have invented a new, original, and ornamental Design for Double-Edge Razor Blade Sharpener, of which the following is a specification, reference being had to the accompanying drawings, forming part thereof.

Fig. 1 is a perspective view; Fig. 2 is a side view and Fig. 3 is a top view, showing our new design for a double-edge razor blade sharpener.

We claim:

The ornamental design for a double-edge razor blade sharpener as shown.

FRANK WAVPOTICH.
LOUIS F. WANEK.
